PORTABLE BRIDGE STRUCTURE

Ivor B. Yassin, Cambridge, Mass.

Application January 6, 1943, Serial No. 471,460

12 Claims. (CL. 14—1)

This invention is a continuation in part of application Serial No. 178,829, filed December 8, 1937, and a continuation in part of application Serial No. 358,786, filed September 28, 1940, on Portable bridge structure.

This invention relates to portable bridge structures. The main object of the invention is to provide a portable bridge structure that may be easily placed into and moved from a position. Such a structure is to be used primarily in place of the fixed and expensive under or overpass structures used at busy crossroads or intersections.

Another object is to provide a bridge structure composed of several sections mounted on trucks or mobile units which may be rolled into and out of position for assembly and disassembly.

Another object is to provide a bridge structure made of several trussed sections, whose trusses can be expanded when in use and contracted for portability and/or adjustable for strength purposes.

Another object is to provide a compact portable two way bridge structure that will, when assembled in place on a road that crosses a main highway, occupy only a part of the width of that road and still give ample width for cars moving in both directions. This arrangement will allow traffic to enter the main highway from the crossroad or pass over the main highway without interruption.

Another object is to provide an inexpensive and safe type of crossroad structure that approaches the safety of a "Clover-leaf" type of crossing without its great expense for construction.

Another object of the invention is to provide a traffic control system at crossroads that is safe because it provides unidirectional flow of traffic at all times.

Another object of the invention is to provide a compact type of structure easily adapted for military or emergency use.

Other objects and advantages of this invention will become apparent as the description proceeds. I do not wish to be limited to the specific details as described below. They are to be taken as representative structures only and not limiting; the limitation to be only within the scope of the appended claims.

In the drawings:

Figure 1 shows an elevation of a double deck type of a bridge structure of the invention positioned across the main highway to be used preferably on narrow crossroad intersections with the main highway.

Figure 2 shows a diagrammatic plan view of a main highway and crossroad intersection at which the structure of the type shown in Figure 1 is employed.

Figure 3 shows an elevation of a cantilever half section unit of a single deck type of bridge structure for use at highway intersections or general purpose use.

Figure 4 shows a front elevation of the mechanical arrangement used to effect changes in the load truss depth with the use of support bent labeled B and D of Figure 3.

Figure 5 is a side elevation section taken on Figure 4, indicated by broken line 5—5.

Figure 6 shows the side elevation, partially sectioned, of the emplacement means of support bent labeled D and C of Figure 3.

Figure 7 is a view looking up at the bottom of the emplacing unit labeled C on Figure 3 with the emplacement receptacle and ground deleted for clearness.

Figure 8 shows typically the side elevation of the details of a section of the expandable and contractile load support truss labeled EE on Figure 3.

Figure 9 shows a section through the pivotable and detachable auxiliary pedestal used for intermediate support in the case of long spans shown on Figure 3.

Figure 10 shows the side elevation section of the ground emplacement means labeled A on Figure 3 for the cantilever load support truss.

Figure 11 is a top view partial section taken on Figure 10 indicated by broken line 11—11.

Figure 12 shows a section of the pin connection joint of the hydraulic or pneumatic ram used for tilting or raising or lowering the bridge load support trusses from the support places of the transporting trucks.

Figure 2 shows a main highway 1 having a parkway 2 in its center dividing the road so that the traffic travels in one direction only on either side of the parkway. The crossroad 3 is of narrow width in this case to take the portable bridge

5 of the type shown in Figure 1, which is designed to carry two levels of traffic. A single level type shown in Figure 3 with two sections side by side can be used in place of the two level type for wider crossroads and both modifications will be described positioned in an intersection, although only the double level bridge 5 is shown thus positioned.

In the single level case the crossroad 3 must be of sufficient width to take two bridge sections shown in Figure 3 side by side which allow two cars to pass each other at all points including

the ground level. It is a two-way single-level pass. Figure 2 shows by arrows the directions of traffic flow. It is to be noted that right turns can be made to and from the main highway without hazard or interference with the straight flow of traffic. For safety, in highways with parkways, left turns at the immediate crossing would be eliminated. Such turns could be made from the crossroad by making a right turn into the main highway and then making a U turn into the other lane of the main highway across the parkway 2 at a turn 4 expressly provided for that purpose a short distance from the intersection. A left turn from the main highway into the crossroad would be accomplished by crossing the crossroad under the bridge on the main highway and then making a U turn into the other lane of the main highway at the turn 4 provided for that purpose and, if desired, making a right turn into the crossroad. It is to be noted that with my portable bridge structure and the routing of traffic as indicated above, the hazard reduction and safety resulting from a "Clover-leaf" type of crossing construction is obtained without the great expense of such an arrangement.

The bridge structure 5 shown on Figure 1 consists of cantilever sections 8 and 9 joined to pier sections 10 and 11 respectively, by means of pin joints 12 and 14. Each section 8 and 9 is designed to be distributed in weight and balance so that each may be carried by one truck or other mobile mount. Each of these sections is furthermore designed to have two truss-supported road levels, 6 and 6', which are arranged one beneath the other in the same vertical plane when at ground level and side by side in the same horizontal plane when at the highest level, namely at joints 12 and 14. This arrangement is clearly shown by the arrows in Figure 2. It is to be noted that the entrance to the bridge for traffic in each direction is not obstructed. The exit in each case is beneath the entrance for the opposite direction. Adequate arches, 7 and 7', are provided for the passage and clearance of pleasure cars and light trucks, and the grades of roadways 6 and 6' are made capable of being negotiated by all standard cars. Due to the length of the bridge it is preferably constructed of three or four sections, four being illustrated in Figure 1. The end sections 8 and 9 are similar and consist of upper roadbed 6 and lower roadbed 6', a continuous roadway being 6-6', supported by trussings suspended from girder bents 15 and 15', which are mounted at one end of movable trucks 16 of proper design to carry such truss structures. The trucks may be connected to the truss structure by hydraulic rams 31-31' and detachable pin joints 80, as shown in Figures 3 and 12. Also, trucks 34 may be substituted for truck 16. In position, the bases of the bents 15 and 15' are set into the ground in emplacements 20 and 23 respectively. The structure of the bent and emplacement may be as illustrated in Figures 3 to 7, inclusive. Where the cantilever section structures meet the road, ground anchorages are provided at 18, 19, 24 and 25.

The central pier sections, 10 and 11, needed because of the length of the bridge, are also similar and are mounted on trucks 16', which trucks are in the line of parkway 2 when set in position. These sections are joined together by pin joint 13 and are also provided with ground emplacements, 21 and 22, for the truss bents 17 and 17' respectively.

While the double-level type is for narrow cross-

roads, the single level type shown in Figure 3 can be used for wider crossroads in the same way as the double level type and both types can be used without the pier sections 10 and 11 if there is no central parkway. In case the required span is very long, intermediate support may be provided by auxiliary pedestal 33 shown in Figure 3.

In the case without a central parkway cross traffic will not interfere with the through traffic 10 on the main highway and right turns to and from the main highway may be made without interference. Left turns, however, will have to be made at the center of the intersection in the usual way, or by entering the side street, turning there at a rotary to enter the bridge, and crossing over to turn again at another rotary on the other side so as to make a right turn into the highway. This latter traffic movement also gives the "Clover-leaf" advantage.

The double-level bridge takes up only one lane width of the crossroad and is, therefore, especially adapted for use on narrow crossroads. At street level the entrance and exit are one beneath the other in a vertical plane. To keep the bridge two-level throughout would involve difficult, awkward and costly construction; therefore, it is so designed that it becomes single level when the high point is reached.

Figure 3, in addition to showing the single-level type bridge with its truss-supported roadbed, support bent, auxiliary pedestal 33, emplacements, and trucks 34, shows the arrangement whereby the truss depth may be increased when the bridge is set up for use under loading and decreased for portage. By diminishing the height of the bent and truss and being able to up end part of the roadbed, a compactness is attained that greatly enhances the portability features and general practicability of the structure. It is obvious that the same can be achieved with the double level bridge's upper roadway support trusses, together with similar adjustments for the lower roadway support trusses, if desired. The same means shown in the collapsing of the 40 upper roadway support trusses can be employed on the main support bents and side struts of the lower support trusses, though not shown, since the collapsing of the lower trusses is of minor importance compared to the collapsing of the upper trusses. The truss depths are the main factors of the load carrying capacities of the bridges. The truss depth variation for different loadings is a very useful function, as most often happens when a shallow trussed bridge is designed for one loading and then is made to carry an augmented loading as might arise in military situations or in change of locations with resulting change in the type of traffic.

The load support trusses in Figure 3 consist of upper tension chords 26 and 27, struts 29, roadbed side girders 30, and support bent B-D-C. The intermediate struts 29 are fastened at both ends by pin joints 28 and 38 (Figure 8). The ground anchorage is indicated by A. A side guard wall 32 restrains the collapsed truss during portage. Girder 30 is joined to bent leg D by any suitable connection. Member 35 is a heavy support strut for attachment of an auxiliary section of trussed roadbed in order to decrease the grade. The auxiliary section of trussed roadbed is a length of roadway with adequate side trussing to carry the load, and one end of which is attached to members 35 at their bases so that the edge of this auxiliary roadbed section rests on the existing trussed

roadbed 6—6' (Figures 3 and 9). The other end of the auxiliary roadbed section rests on the ground. A similar auxiliary roadway may be used with the roadbeds of Figure 1.

The entire cantilever unit is supported during portage by trucks 34 by means of hinged support struts 79, which are detachable or adjustable as shown by slots, and telescopic force rams 31—31'. Struts 79 are simple structural members, such as angles or channels, each having one pin and the other a hinged portion with a slotted end. These struts are attached by hand to pins shown on trucks 34 and bent leg D or chord 30, serving the minor purpose, when rigidly pinned as shown in Fig. 3, of preventing side sway of the bridge unit during moving. In setting up or taking down the bridge unit they are loosened and can be removed entirely or allowed to move out of interference by the jointed, slotted section. Figure 3 shows the unit in erected position. For portability the load truss is completely collapsed within the confines of sideguard 32, and pedestal 33 is pivoted to attach under or over the bridge roadbed, or completely detached.

Figure 8 shows the side elevation details of the upper tension chord 27, intermediate strut 29, and roadbed side girder 30, all shown typically at EE on Figure 3. One strut 29 and one joint 38 are shown as typical and an identical strut and connection belong on girder 30—but sufficient disclosure is assumed by what is shown. In Figure 3, the drawings are to such a small scale that struts 29 are made to meet at one point in girder 30. Actually, clearances are preferred, and in Figure 8 this is shown by the position of 38, in line with, but away from the joint made by fittings 36 and 37. All roadbed joints will not have 36 and 37 type fittings but will have connection 38 for struts 29. This construction is typical for any joint.

Figure 9 shows a section of the upper pin connection terminal of the bridge unit with an attached pedestal and adjoining transverse roadbed. Pedestal 33 can pivot about or be removed from side girder 30 by means of the pin in bearing 39.

The intermediate struts 29 are released from upper tension chords 26 and 27 by pulling pins in joint 28. The struts then pivot about pin joint 38 to lie along the top of side girder 30. The pin joints near the ends of the structure are made as union fittings permitting the tension chord to be in two parts 27 and 27' so that extension of the upper chord during lowering of bent is allowed. An alternative method shown in Figure 10 for chord 26 will be described further on. Also the roadbed side girder has a union pin joint allowing it to be in two parts 30 and 30'. The male fitting 36 has lug of joint 38 integral with it. Fitting 36 which is attached rigidly to girder part 30' fits into 37, the uniting fitting attached rigidly to girder part 30. Fittings 36 and 37 abut against each other in a 180 degree line by construction as shown in Figure 8, and can pivot only in one direction from the 180 degree line as indicated by the cutaway clearance. Thus when the bridge is erected, parts 30 and 30' are held rigidly by this abutment of the fittings against each other and the pinned attachment of strut 29 at joints 38 and 28. With struts 29 and chord 27' detached, that part of the roadbed can be ended and folded over thus decreasing the length of the truss. The same can be done at the ground end of the unit, though not shown. The pedestal

75 33 may be detached or folded over to lie on the roadbed.

As an alternative or additional arrangement the chord 26 and also chord 27 may be attached to girder 30 at their ends in the manner shown by Figures 10 and 11. In these figures chord 26 is shown as provided with a slot and notches for cooperating with lugs 78 on plate 76 attached to girder 30. Plates 75 attached to chord 26 are provided with a lift bar 77. By means of the lift bar the lugs 78 may be positioned in either one of two locations in the notches, or in the slot. In this manner the truss may be given two distinct depths or be substantially collapsed. Suitable struts 29 may be provided for the two depths of the truss. Although two depths of the truss by notch locations are shown, a number of depths may be provided for by the suitable number of notches appropriately located.

20 Member 41 is the telescoping upper part of bent of pipe cross-section. Receptacle part of bent, 42, shown in Figure 5 and more clearly in Figure 7, has guide ways 43 of circular inner bearing to allow sliding fit with 41, and rectangular outer bearing for attachment to member 42. Member 40 is pipe cross member for transverse support of load trusses and is welded as shown to 41. Cover 52 is made to fit to 42 and as guard for pin joint 47. Two heavy bearing blocks 48 and 48' support pin 47 about which chord members 26 and 27 pivot with washer 53 strengthening end connections as shown. Pin 49 keeps bearing block 48 in place and 48' is edge welded. The dotted lines show position of chords 26 and 27 in raised position and the solid lines in lowered position, giving the extent of rotating motion. Locking lugs 54 keep the extensible member 41 in place when in the raised position, as shown by the dotted lines. They are pulled by hand out of slots 55 as shown in solid lines, thus offering no obstruction to the up and down movements of member 41. As many slots 55 can be used as the various adjustments of the truss call for. In this case an intermediate slot is shown (dotted) for a shallower truss depth, thus showing three truss depths, maximum, intermediate and minimum.

45 Pins 44 run through member 42 and bear in extensions of guide ways 43. Crank handle 45 integral with one pin 44 is turned, thus turning gear 51 meshed with gear 51', both being meshed with racks 50 and 50', respectively, which are fastened to 41. This motion lowers extensible member 41 to the position shown, and in consequence upper chords 26 and 27 and struts 29 lie within side guard 32 of Figure 3 and indicated further in Figures 13 and 14. Slots 43' in the sides of member 41 allow movement of 41 with respect to pins 44.

60 The bridge section is now completely collapsed for transport, and it is necessary to release the anchorage A for the section ground terminal and anchorage C for the girder bent legs.

65 To release anchorage C in Figure 3 it is first necessary to pull out lock bar 56 in Figures 6 and 7 as shown by the dotted lines. The lock units consist of a casing and a slidable bar 56, which when pushed in as shown prevent the anchorage insert 59, a lightened steel casting, from sliding upwards when the compressive column load of the girder bent leg 42 is applied during operation of the bridge. The leg loading will be always compressive, but because of structural movements due to rolling vehicle impact loads, there will be momentary load application and re-

lease effects, which will tend to cause destructive vibrations in the bridge structure. Accordingly, to effect both the means to lift insert 59 out of its receptacle 60, a steel casing set in concrete 66, when the bridge unit is to be moved, and to take up the vibratory motion of bent leg 42 under impact loads, a slight amount of play, shown in Figure 6 is allowed between the lug 56 and the top of insert casting 59, and an oleo-rubber shock absorber shown by 57, 58 and 62 is attached firmly to insert 59 by sealed outer oil cylinder 58.

The shocks are then taken up by rubber discs 57 and oil cylinder 58, since in moving up cylinder 58 tends to telescope inner oil cylinder 62, which forces the oil in cylinder 58 through needle orifice 63 in to cylinder 62. Since slidable plate 65 is attached by a close sliding fit to outside of cylinder 58, its upward movement compresses rubber discs 57, which together with inner cylinder 62 are restrained at the top by plate 64 fastened firmly to girder 42. Reinforcing Z-members 61 assist in proper transference of the loads through the locking bars 56 from the girder 42 to the ground through casting 59. The Z's are cut to allow sliding of 59. U-rods hold the rubber discs in place as shown.

By reason of the close sliding fit of plate 65 with cylinder 58 a sudden shock will cause the two parts to seize and thus produce a compression in rubber discs 57 when cylinder 58 moves upwardly. The rubber discs then aid the oil and air in cylinders 58 and 62 in producing a shock absorber action. However, when cylinder 58 is slowly moved upwardly to withdraw insert 59 from receptacle 60, the sliding fit of plate 65 permits such movement. The shock absorber 57, 58, 62 is actually a combination of the ordinary oleo-pneumatic and oleo-rubber types. That is, air in the cylinder 62 is under compression and is intended to sustain the ordinary load of the bridge. The rubber discs come into use only momentarily, when the structure is submitted to a sudden overload. Oleo-pneumatic, and oleo-rubber shock absorbers of the kind used here are more clearly shown on page 156 of Metal Aircraft Construction, by M. Langley, 1st ed., 1932, published by Gale and Polden, Ltd., of London, England.

To release anchorage A in Figure 3, it is necessary to pull out lock pins 71 shown in Figure 10. These pins inserted at the ground level pass through concrete emplacement 67 which has steel receptacle 69 imbedded in it, which in turn houses extension tongue 70. The pins 71 thus lock tongue 70 firmly to the concrete emplacement. The tongue 70 has a bearing block 73 integral with it and to which is attached handle 74. By grasping handle 74 the tongue may be withdrawn from the receptacle 69 and made to take the position in side channels 68 shown by the broken line. Thus the terminal A of Figure 3 is released from the ground. Sufficient clearance is left for the movements of chord 26, as tongue 70 can be shifted easily after release.

In the locked position, block 73 bears against collar 72 which is welded integral with side channels 68 having oversized flanges 68', and which in turn are continuations of the web channels of roadway bed side girder 30.

Thus the load is transferred from upper chord 26 to lower chord 30 by means of union plate 76 and pins 78. In turn the load is transferred from chord 30 through side channels 68 to collar 72, which being restrained by bearing pressure of block 73 makes the load go to the ground.

With the bridge section thus made ready for transport the raising and lowering units 31—31' are coupled by pins 80 and adjusted by the movement of piston 31 in casing 31', to tilt the bridge trussing and connected roadbeds, and to take the bridge load when inserts 59 of the girder bent legs are raised by remote pumping of the oil out of cylinder 58 permitting it to telescope cylinder 62. To erect the bridge the reverse of the procedure herein described is followed.

In order to operate the piston 31 and the shock absorber cylinder 58 a reservoir of oil is provided. A variable speed motor run from the truck power plant generator or batteries drives a variable delivery centrifugal or gear pump, capable of reversing direction, to a system of outlet valves called a selector valve, which controls the flow of oil to and from cylinders 58 and 31'. Should oil be desired in cylinder 58 for operation of the shock absorbing function of C, it is pumped by the operator to cylinder 58 and its proper valves closed to keep the oil in the local systems of shock absorbers C—D. Should it be desired that casting insert 59 be raised, the proper valves are opened and the oil in cylinder 58 is pumped out and back into the reservoir. The pumping out of oil tends to create a vacuum in cylinder 58 which will tend to rise to telescope cylinder 62, if the system is airtight as it should be. The lugs 56 must first be released to allow this to happen as shown in Figure 6. If there is air leakage in the lines, the castings can be raised by hand, telescoping the cylinders 58 on cylinders 62. In the same way the rise and fall of piston ram 31 in cylinder 31' can be controlled. Each system operates independently of the other because of the selector valve and independent hydraulic lines. The necessity and obviousness of proper valves are inherent in such systems and since such hydraulic systems are common on trucks further illustrations are not necessary.

One of the important features of the invention is that the bridge sections may be rolled on their mobile mounts into and out of position at will and assembled in a short time. Therefore, they may be quickly put into position for weekends or holidays on roads leading out of cities to beaches or other pleasure places—or wherever it becomes known that traffic will be heavy. When not needed the bridge units may then be easily removed and stored on nearby vacant land.

Being constructed of light weight, high-tensile-strength materials of the types and kinds now being used in the aircraft industry, the weight of the bridge sections would not be excessive and could be easily carried on ordinary trucks.

The portable bridge lends itself for use as a pedestrian bridge over busy crossings and I contemplate the use of similar portable structures for such purpose.

It is also contemplated that the bridge structure may be designed wide enough to carry more than two lanes of traffic or that two bridge structures may be placed in parallel to provide several lanes of traffic.

I do not wish to limit myself to any particular design of collapsible truss, truck, roadbeds, emplacements or bridge units. It is to be understood that a pair of trucks 34 may be considered to comprise a mobile mount or truck for an end unit, either of the single type shown in Figure 3 or the double type of Figure 1.

I claim:

1. In a portable vehicle-bridge structure of the class described, adapted for use on a road inter-

section, a plurality of prefabricated units comprising end units, each unit having two inclined-roadways with exit emplacing means united by structural trussing of a continuous type, and being joined together with intermediate double roadway units to form a unitary vehicle-bridge structure; additional roadway lengths as continuations of existing lanes, adapted to be attached to strengthened struts of the side trusses of the units to vary the inclination of the roadways; the inclined roadways of the end units being attached to transverse vertical support-frames with extensible lower sections of the columns thereof; each unit being coupled in combination with a mobile mount, so that it may be rolled into position for the assembly of the units and out of position on disassembly; said units, when they are set into position on a road and joined together, having the extensions of the transverse vertical support-frame lower columns slide into fixed emplacements so that all bridge loadings are removed wholly from the mobile mount to the ground; said assembled vehicle-bridge structure providing for a double traffic flow parallel to each other at the center of the bridge and diverting to an exit or entrance for one lane of traffic under the other exit or entrance in a double-level roadway combination, one exit or entrance being at a distance from the other; said assembled vehicle-bridge structure providing an overpass crossing over a main highway without obstructing the main highway.

2. In a portable vehicle-bridge structure of the class described, a plurality of prefabricated units comprising end units with double, inclined-roadways interlocking with intermediate units to form a unitary vehicle bridge structure, said inclined-roadways having emplacing means at the exits and being held in relative juxtaposition by vertical side-trussings and transverse frames; the combined inclined-roadways, side-trussing and connecting transverse-frames therefor being attached to main, vertical, transverse support-frames with extensible columns having emplacing extensions movably attached at the bases of the said main, support-frame columns; the extensions being adapted to be received in fixed emplacement of a prepared type and thereby supporting the units when they are set into position on a road and joined together; each unit being detachably mounted on a mobile-truck, so that it may be moved into or out of position for assembly or disassembly; each unit having actuating means comprising motivated devices at the bases of the main, support-frame columns connected to the movable column extensions for fixedly emplacing the extensions in the prepared-type emplacements when in position without altering the relative positions of the bridge trussed units and the mobile truck; said assembled vehicle bridge structure providing for two traffic lanes, the exit or entrance for one lane being at a distance from the exit or entrance of the other, both exits or entrances being in the same vertical plane; said lanes diverging by inclination from a two-level position at the exits or entrances to a two-lane parallel position at the high point of the overpass.

3. In a portable vehicle-bridge structure, a plurality of prefabricated units comprising end units having double, inclined-roadways with end emplacing means and interlocking with intermediate units to form a unitary vehicle bridge structure; said inclined-roadways of each end unit being held in relative juxtaposition by connected, vertical side-trussings and transverse frames, and

the combination of roadways, side-trussing and frames being attached to a main, vertical transverse support-frame having extensible lower sections of the support columns thereof for interlocking with fixed, prepared type road-emplacements; instrumentalities for changing the height of the upper sections of the support columns for portage; each unit being detachably mounted on a mobile-truck; and each unit having actuating means comprising motivated devices connected to the movable column extensions at the bases of the main, support-frame columns for emplacing said extensions fixedly in the prepared-type emplacements when assembled into position, without changing the relative positions of the bridge-trussed units and the mobile-truck; said assembled vehicle-bridge structure comprising a two-lane, double-level entry bridge with one lane vertically over the other at the exits or entrances and one lane beside the other in the same horizontal plane when at the high point of the overpass.

4. In a portable bridge structure, a side-truss supported, inclined roadbed unit, detachably carried by a mobile mount; additional roadway lengths as continuations of the existing roadbed lanes adapted to be attached to strengthened struts of the side-trusses of said unit for varying the inclination of the roadbed; instrumentalities for emplacing the unit fixedly into prepared-type ground emplacements for operation; contractible and extensible means for varying the depths of the side trusses of the unit for portage, said means comprising main, mutually-slidable columns containing the emplacing instrumentalities in the bases thereof, and member-connected transversely to form a frame supporting the road-bed; detachable intermediate struts connecting the upper and lower chords of the side-trusses for depth being cooperative with said slidable columns; and instrumentalities effecting the corresponding relative movements of the upper chords of the unit side trusses, the last named structures including the main support columns having attached the upper chords and fixedly attached the lower roadbed side-chords thereto, together with the detachable chord connecting intermediate struts.

5. In a portable bridge-structure, a side truss supported, inclined roadbed unit, detachably mounted on a mobile truck; the side-trusses of the unit having main, support columns with lower, extensible sections for emplacing fixedly into prepared-type emplacements and member-connected transversely to form a frame having the roadbed attached thereto; telescoping upper-column sections into receptive lower column sections; detachable intermediate struts connecting the upper and lower chords of the side-trusses for depth being cooperative with the said slidable columns; the upper chords being movably attached at one end to the upper telescoping column sections, and the opposite ends of said upper chords being slidably interlocked with the ends of the lower chords; said side-trusses of the unit being adjustable in depth for different loading capacities.

6. In a portable bridge-structure, a side-truss supported, inclined roadbed unit, detachably mounted on a mobile-truck; the side-trusses of said unit having main support columns at their greatest depths with extensible lower sections of the columns for emplacing fixedly into prepared-type emplacements and telescoping upper-column sections, each upper column section comprising an inner column moving extensibly or contractibly in an outer column together with means

to actuate said inner column slidably; a transverse bar therewith connecting the upper, inner, main-support column sections of the side-trusses and the horizontal roadbed transversely connecting the receptive outer column sections thereof; and pivotable means for the upper chords of the side-trusses attached to the inner-column sections whereby corresponding relative movements of the upper chords may be effected during the telescoping action of said inner column sections. 10

7. In a portable bridge-structure, a side-truss supported, inclined roadbed unit, detachably mounted on a mobile-truck; the mounting between unit and truck comprising mutually slideable members so that the relative positions of the bridge trussed unit and the mobile truck may be altered during emplacement; the side-trusses having main support-columns, connected transversely by members to form a frame supporting the roadbed, the columns having extensible lower-sections for emplacing fixedly into prepared-type emplacements and telescoping upper sections linked with corresponding relatively-adjustable upper chords of the side trusses, and detachable intermediate struts connecting the upper and lower chords of the side-trusses being cooperative with the slideable columns; sections of the lower chords also being pivotable for shortening the length of the roadbed for portage. 15

8. In a portable bridge-structure, a side-truss supported, inclined roadbed unit, detachably mounted on a mobile-truck; the side-trusses having main, support-columns with telescoping upper-column sections, adjustable truss-members being cooperable with the slideable upper sections of the columns, and extensible lower-column sections for emplacing into the ground; said extensible lower-column sections comprising elements to fit into prepared-type emplacements together with actuating means to propel said elements into the emplacements and to withdraw the elements from the emplacements; said actuating means also being a shock absorber connection between the bridge unit and the emplacements. 30

9. In a portable bridge-structure, a side-truss supported, inclined roadbed unit, detachably mounted on a mobile-truck; the side-trusses having main support-columns with telescoping upper column sections, adjustable truss-members being cooperable with the slideable upper sections of the columns, and extensible lower-column sections for emplacing into the ground; said extensible, lower-column sections comprising elements to fit into prepared-type emplacements and actuating means to propel the elements into the emplacements for the operation of the bridge unit and to 45

withdraw the elements from the emplacements telescopically into the bases of the main support columns when the bridge unit is to be moved; said actuating means also effecting dampening for the vibratory loads of the support columns under the impact loads. 50

10. In a portable bridge-structure, a truss-supported bridge end unit, comprising an inclined roadbed, detachably carried by a mobile-mount; the trusses being attached to main support-columns with extensible ground anchorages at the bases of the truss main support columns, and terminal, extensible-ground anchorages at the bases of the roadbed slope; said terminal, extensible ground anchorages comprising slideable elements to lock fixedly into the prepared-type emplacements, actuating instrumentalities to propel and withdraw the elements, and locking pins for the extensible elements; said extensible elements adapted to fix the bridge end unit to the emplacements against cantilever loading. 55

11. In a portable bridge-structure, a truss-supported, bridge end-unit, comprising an inclined roadbed, detachably carried by a mobile-mount; the trusses being attached to main support-columns; said roadbed having terminal, extensible ground anchorages at the base of its slope, and extensible ground-anchorages at the bases of the truss, main support-columns; said main, support-column anchorages having slideable elements to insert into the prepared-type emplacements, actuating instrumentalities to propel and withdraw the elements telescopically in the main, support-column, lower fixed-sections, and locking lugs to limit the travel of the extensible elements when emplaced. 60

12. In a bridge end-structure of the class described, a sloping roadbed unit, pivotably mounted on a mobile-truck; said mounting between unit and truck comprising mutually-slideable members so that the relative positions of the bridge trussed unit and the mobile-truck may be altered during emplacement, and cooperable terminal ground-anchorages for transferring all the loading from the bridge end-unit to prepared, fixed emplacements; said terminal ground-anchorages comprising slideable extensions at the base of the roadbed slope with locking pins and extensible elements at the bases of the truss, main support-columns with locking lugs; said extensions of all ground anchorages adapted to be withdrawn from the emplacements telescopically into the contiguous supporting structures when the bridge end unit is tilted on its pivotable mountings for portage. 65

IVOR B. YASSIN.

CERTIFICATE OF CORRECTION.

Patent No. 2,363,767.

November 28, 1944.

IVOR B. YASSIM.

It is hereby certified that error appears in the printed specification of the above numbered patent requiring correction as follows: Page 1, first column, line 5, for "Portable bridge structure" read --Portable bridge structures--; and second column, line 24, for "contractivle" read --contractible--; page 3, first column, line 32, for "drawings are" read --drawings is--; line 40, after the word "joint" and before the period insert --desired near the end of the truss--; page 4, first column, line 21, for "Reinforming" read --Reinforcing--; page 5, second column, line 1, claim 3, for "side-trussing" read --side-trussings--; same column, line 44, claim 4, after "having" insert --movably--; and that the said Letters Patent should be read with this correction therein that the same may conform to the record of the case in the Patent Office.

Signed and sealed this 8th day of May, A. D. 1945.

Leslie Frazer
